[57] **CLAIM**

The ornamental design for a flush trim collar assembly, as shown and described.

DESCRIPTION

FIG. 1 is an exploded view of the flush trim collar assembly, the support ring and finishing ring being separated for convenience of illustration;

FIG. 2 is a top view of the support ring, the right side, left side, and bottom side views being identical thereto, the finishing ring being omitted for purposes of disclosure;

FIG. 3 is a front view of the support ring;

FIG. 4 is a rear view of the support ring;

FIG. 5 is a top view of the support ring;

FIG. 6 is a top view of the finishing ring, the right side, left side, and bottom side views being identical thereto, the support ring being omitted for purposes of disclosure;

FIG. 6 is a front view of the finishing ring; and,

FIG. 7 is a rear view of the finishing ring.
